UNITED STATES PATENT OFFICE.

HENRI TOBLER, OF HACKENSACK, NEW JERSEY, ASSIGNOR TO AMERICAN BROMINE COMPANY, OF MAYWOOD, NEW JERSEY, A CORPORATION OF NEW JERSEY.

ELECTROLYTIC APPARATUS.

1,380,853.

Specification of Letters Patent. Patented June 7, 1921.

Application filed November 8, 1920. Serial No. 422,431.

To all whom it may concern:

Be it known that I, HENRI TOBLER, a citizen of the United States, residing at Hackensack, in the county of Bergen, State of New Jersey, have invented certain new and useful Improvements in Electrolytic Apparatus; and I do hereby declare the following to be a full, clear, and exact description of the invention, such as will enable others skilled in the art to which it appertains to make and use the same.

The apparatus of the present invention is suitable for the electrolysis of brine, as in producing hypochlorites, and is particularly suitable for use on natural brines, such as those of Michigan and the Ohio river valley, when a halogen such as bromin is to be recovered from the brine by electrolytic oxidation followed by known methods of separation, purification and absorption.

The apparatus is so constructed that when bromin alone is the desired halogen, the electrolysis can be conducted in such a manner as to have a recovery of bromin well above 95%. The apparatus is capable of exact regulation of electrical input to brine flow, so that over-oxidation of the brine can be accurately gaged to the needs of any particular brine, thus insuring complete liberation of all of the bromin without the liberation of more chlorin than is useful in setting free the bromin from its chemical compounds in the brine.

The apparatus is of simple and cheap construction; can be built in standard units easily interchangeable; can be assembled to suit the voltage of the source of electricity, and any unit is readily replaceable at will if occasion should require.

The electrical elements are effectively insulated, the brine containers and conduits are not subject to rapid destruction either from electrolysis or otherwise, and all are adequately protected against leakage. The electrodes and other surfaces subject to normal electrolytic corrosion can be easily renewed with but short interruptions to the operation of the apparatus, and all of the working parts can be readily and thoroughly cleaned of the sediment which ordinarily collects in an apparatus used for the electrolytic oxidation of a natural brine.

In the accompanying drawing, there is illustrated one embodiment of the apparatus comprising a series of containers each adapt-

ed to serve as cathode of an electrolytic cell, and each provided with a carbon anode preferably positioned concentric with the container. Between each anode and its container, the brine to be electrolyzed is circulated. Pipes or conduits of non-conducting material form tortuous paths from one container to the next, so that the brine undergoes progressive electrolysis in the several units or cells of the apparatus. The number of cells thus connected together in series can be proportioned to the voltage of the electrical energy conveniently available; but for a 115 to 125 volt direct current supply, it is preferable to use 24 cells thus connected in series. The several electrolytic cells being connected in electrical series are at different electrical potentials, and the quantity of current sent through the series is proportioned to the degree of electrolysis or oxidation desirable with any particular brine. But for the liberation of bromin from its chemical combinations in natural brines, such as those of Michigan and of the Ohio river valley, it is preferable to use a current density which will slightly over-electrolyze the brine so far as concerns its bromin content, or, in other words, will yield some free chlorin together with substantially all of the bromin.

The single figure of the drawing is an elevation partly in section of two units of a series of electrolytic cells through which a bromin-bearing brine may be passed for electrolytic oxidation preparatory to recovery of the bromin from the brine.

Each unit or cell of the electrolytic apparatus illustrated in the accompanying drawing as the preferred embodiment of the present invention, comprises a container 1, which is of tubular shape, vertically disposed, and consists of a single iron casting terminating at the bottom in a threaded opening 2, adapted to receive a threaded bushing 3 of hard rubber into which is threaded or otherwise suitably secured an anode 4 of carbon, preferably graphitic carbon, of cylindrical shape. Thus, there is left between the cylindrical and centrally positioned anode and the cast iron container which is to serve as cathode, a vertical annular space through which brine can be circulated in the desired direction, and can be electrolyzed by current of suitable voltage passing from anode to cathode through the

brine. Each cast iron container is sur-
mounted by a T-fitting 5 of tile, or like
insulating material, with a calked bell-joint
6 between the tile and the metal container
5 to insure a fluid-tight connection which can
be taken apart in case the apparatus is to be
repaired. The tile fitting for the first con-
tainer of the series is equipped with an inlet
conduit 7 through which the raw brine is
10 supplied to the apparatus, this inlet being
so arranged as to maintain a brine level
throughout the apparatus well above all
metal parts, as, for instance, at the level in-
dicated by a dotted line in the drawing.
15 At the bottom of fitting 1 and cast inte-
grally therewith is an elbow or extension 9,
the lower leg of which is provided with a
clean-out opening closed by a plug 10, and
the upper leg of which is connected through
20 a bell-joint 11 with a pipe or conduit 12 of
insulating material, such as tile pipe, which
by means of a coupling 13 communicates
with the inlet opening of the next tile fitting
5, thereby forming a tortuous path for brine
25 from the bottom of one container to the top
of the next. This insures free circulation of
the brine throughout the series of electro-
lytic cells, but limits to a negligible amount
the leakage of electrical energy from one
30 anode to more remote cathodes of the series.

Each carbonaceous anode is provided with
an encircling spring-clip 14 to the bolt of
which is attached a cable 15 by which the
electrical current is supplied to the anode.
35 Each cast iron cathode is provided with a
binding-post 16 to which one of these ca-
bles 15 is connected, so that direct current
entering the first anode 4 from the dynamo,
or other source of electrical energy, passes
40 through the brine to the metal container of
the cell, and then out through cable 15 to
the next anode, and so on throughout the
entire series.

The chemical effect of electrolysis on a
45 natural bromin-containing brine is, first, to
liberate the bromin from its chemical com-
binations in the brine, and, second, to liberate
the chlorin from its chemical combina-
tions, the voltage of decomposition being
50 somewhat higher for chlorids than for bro-
mid. The free bromin remains for the most
part mechanically absorbed in the brine, and
the free chlorin will chemically react on any
unreduced bromids in the brine to liberate
55 an equivalent quantity of free chlorids.
Consequently, in the electrolysis of a nat-
ural brine in this apparatus, some of the re-
sulting free bromin may come from elec-
trolysis directly, and some may come as a
60 secondary product, resulting from the elec-
trolysis of bromid. The apparatus illus-
trated in the drawing is especially conducive
to this secondary action, for any bubbles of
chlorin liberated on the anode must pass up-
65 ward through a considerable column of

downwardly moving brine before they can
escape at the surface of the brine. There
is, therefore, good opportunity for intimate
contact between the chlorin and the brine,
and much of the chlorin therefore is used in 70
desirable manner when freed bromin is the
ultimate product.

Inasmuch, however, as the current density
may be such as to liberate some free chlorin
and even some free bromin at the top of each 75
column of brine, I provide each tile fitting
5 with a removable wooden cover 17 to pre-
vent the escape of these gases into the cell
room. Also, there is provided at the top of
each of the conduits 12, a vent pipe 18, 80
which may be a rubber hose leading to a
hollow wooden log 19, whereby the gases
may be conveyed away for use in any desired
manner.

The group of electrolytic cells are sup- 85
ported on a frame-work comprising tile
pipes 20 standing on end, with their bells
down, surmounted by timbers 21 on which
are placed wooden beams 22 impregnated
with asphalt, or otherwise treated to render 90
them more resistant to salt brine. Each cast
iron container 1 is provided on either side
with an outwardly extending and integral
foot 23 resting on the top of one of beams
22. And, similarly, each extension or elbow 95
9 has an integral foot 24 on either side of its
bell end to rest on beam 22. This mode of
mounting keeps all of the apparatus in
proper position with the cathodes well insu-
lated one from another. I find it advanta- 100
geous to sometimes inclose the tile pipe 12,
and its coupling 13, in an envelop 25 of con-
crete cast about these members after they
have been installed in position. This con-
crete, as shown in the drawing, covers and 105
reinforces the joints of the tile pipe and
rigidly anchors the pipe to the adjacent pipe
5. When the joints are thus reinforced,
there is little or no danger of the escape of
gaseous bromin into the cell room, and all of 110
the bromin freed from the brine is either
carried along dissolved in the brine, or es-
capes through vent pipes 18 into the main
pipe 19, from which it can be sucked out for
use elsewhere in the system. 115

After the natural or other brine has thus
been circulated through the apparatus and
electrolyzed, and consequently oxidized to the
desired extent, it may be conveyed away to
suitable apparatus for the separation of the 120
bromin from the brine, for its purification
from chlorin, and for its ultimate absorp-
tion in well known manner, to produce
marketable bromin solutions, or salts recov-
ered from such solutions, as, for instance, 125
sodium and potassium bromid.

I am aware that the form of the apparatus
and its method of use herein set forth may
be varied in many particulars, and I contem-
plate such variations as reasonably come 130

within the spirit of my invention, as above described, and as defined by the claims appended hereto.

I claim:—

- 5 1. Electrolytic apparatus comprising a series of metal containers adapted to serve as cathodes at different electrical potentials, means for circulating brine by a tortuous path from one container to another, a carbon 10 anode positioned in each container and about which said brine circulates during electrolysis, each of said containers having an integral extension with a clean-out opening through which sediment deposited from the 15 brine may be flushed out.
2. Electrolytic apparatus comprising a series of vertical tubular iron containers adapted to serve as cathodes at different electrical potentials, means for circulating brine by a tortuous path from one container to another, a part of each tortuous path being of 20 non-conducting material and the remainder being of iron cast integral with its cathode.
3. Electrolytic apparatus comprising a 25 series of vertical cast iron containers adapted to serve as cathodes, means for circulating brine by a tortuous path from the lower part of one container into the upper part of the next container, a part of said path consisting of tile pipe and another part consisting of iron pipe cast integral with the adjacent cathode.
4. Electrolytic apparatus comprising a 35 series of vertical containers adapted to serve as cathodes at different electrical potentials, an insulating bushing at the bottom of each container, a carbon anode mounted in each bushing and about which brine may be circulated, a tubular extension integral with 40 said cathode and provided with a clean-out opening, and an insulating pipe connected with said extension and with the upper part of the next container to serve as a tortuous path for the circulation of brine, substantially as described.
5. Electrolytic apparatus comprising a 45 series of tubular cast iron containers adapt-
- ed to serve as cathodes, a tile pipe surmounting each container, a pipe for circulating brine by a tortuous path from the lower part 50 of one container into the tile pipe which surmounts the next container, a carbon electrode in each container to form therewith an electrolytic cell, means electrically connecting said cells in series to progressively electrolyze the brine as it passes through the 55 series of containers, and means for venting the top of each container.
6. Electrolytic apparatus comprising a plurality of vertical containers adapted to 60 serve as cathodes in an electrical series, means for circulating brine by a tortuous path from one container to another, an anode positioned in each container about which said brine circulates during electrolysis, 65 and gas exhausting means above the brine level in each container to carry away gases liberated by electrolysis and not absorbed by the electrolyte.
7. Electrolytic apparatus comprising a 70 plurality of cast iron containers adapted to serve as cathodes in an electrical series and each provided with supporting feet, a pair of timbers on which said feet rest, an extension integral with each container and provided with a clean-out opening, an anode in 75 each container, and means for circulating brine by a tortuous path from one container into the top of an adjacent container, substantially as described. 80
8. Electrolytic apparatus comprising a series of metal containers adapted to serve as cathodes at different electrical potentials, means for circulating brine by a tortuous path from one container to another, a carbon anode positioned in each container and about which said brine circulates during electrolysis, a pair of timbers on which said containers are supported, and means connecting said anodes and cathodes in series 85 90 relation, substantially as described.

In testimony whereof I affix my signature.

HENRI TOBLER.
